UNITED STATES PATENT OFFICE.

KARL R. AKERLUND, OF CHICAGO, ILLINOIS.

SPRING-MOTOR.

1,385,351.

Specification of Letters Patent. Patented July 26, 1921.

Application filed December 14, 1916, Serial No. 136,943. Renewed January 2, 1920. Serial No. 349,091.

To all whom it may concern:

Be it known that I, KARL R. AKERLUND, a citizen of the United States, residing at Chicago, in the county of Cook and State 5 of Illinois, have invented a certain new and useful Improvement in Spring-Motors, of which the following is a full, clear, concise, and exact description.

My invention relates to motors and has 10 for its object the provision of means whereby a prime motor may operate a load, such as the hands of a clock, through the intervention of a secondary motor, the latter motor being a spring motor and the first motor 15 being preferably a spring motor. The load operating torque is directly furnished by the secondary motor and as the spring of this motor is preferably frequently wound by the primary motor such torque may be 20 substantially uniform.

I will explain my invention very fully by reference to the accompanying drawings showing the preferred embodiment thereof and in which Figure 1 is a front view of such embodiment with the front of the casting structure removed; Fig. 2 is a side view of the equipment shown in Fig. 1; Fig. 3 is a horizontal section taken on line 3—3 of Fig. 1; Fig. 4 is a vertical sectional view taken on line 4—4 of Fig. 1; and Figs. 5, 6 and 7 are detail views of parts of the mechanism and illustrate certain operations, Fig. 7 being a view on line 7—7 of Fig. 4.

Like parts are indicated by similar characters of reference throughout the different figures.

The winding motor employed is preferably a spring motor and such a spring motor may be inclusive of a spring barrel 1 40 which is adapted to rotate and a winding shaft 2 which is normally stationary but which may be turned in a counter clockwise direction in order to wind the coiled tape spring (not shown) which is anchored 45 at its inner end to the shaft 2 and at its outer end to the spring barrel 1. The shaft 2 carries a ratchet wheel 3 that is engaged by a pawl 4 which prevents the shaft 2 from turning in a clockwise direction whereby 50 the spring barrel 1 alone may turn when the winding motor functions. A gear wheel 4 is fixed with respect to the spring barrel to turn therewith. This gear wheel operates two trains of gears, to which gear trains the 55 pinion 5 and the gear 6 are common. The pinion 5 is in mesh with the gear 4 and the

gear 6 that is fixed with respect to the pinion 5 is in mesh with a pinion 7 fixed with respect to a gear 8 that is in mesh with a pinion 9 fixed with respect to a gear 10 that is in mesh with a pinion 11 fixed with respect to a gear 12 that is in mesh with a pinion 13 fixed with respect to a gear 14 that is in mesh with a pinion 15 fixed with respect to a rotating brake element 16 that 65 is preferably in the form of a brake drum. The rotating brake element or drum 16 is normally engaged by a brake 17 to stop the operation of the winding motor. Inasmuch as the brake element 16 is rotatable at a 70 high rate of speed at low torque owing to the speed increasing and power reducing gear train described, but little brake pressure is required. The brake is applied to the brake drum by means of mechanism of which 75 a link 18 constitutes a part and which will later be described. The brake is released by a brake spring 19 having one end mounted at 19¹ upon the frame 19² and its other end engaging the under side of a pin 20 80 carried upon a brake arm 21 upon the outer end of which the brake 17 is mounted.

The gear 6 is also in mesh with a pinion 22 which is fixed upon a shaft 23. The inner end of a torque exerting or load operating coil spring 24 (Fig. 4) is anchored to the shaft 23 and the outer end of this spring is anchored to a spring barrel 25 to which is secured a gear wheel 26 rotatable around the shaft 23. The gear wheel 26 is 90 in mesh with a pinion 27 that is fixed with respect to a gear 28 that is in mesh with a pinion 29 fixed with respect to a gear 30 that is in mesh with a pinion 31 fixed with respect to a gear 32 that is in mesh with a 95 pinion 33 fixed with respect to an escapement wheel 34 that co-operates with an escapement 35 to regulate the speed at which the spring 24 may unwind. When the gear 6 is stationary the shaft 23 is stationary and 100 the coil spring 24 of the secondary motor reacts against the same to perform its work. When the gear wheel 6 is permitted to rotate, which happens when the brake 17 is released, the shaft 23 is turned by the winding motor to wind the spring 24. In either case the spring 24 is constantly unwinding (in the embodiment of the invention illustrated but to which characteristic the invention is not to be limited) to perform its 105 clock hand operating or other function. The speed with which the gear 6 winds the

spring 24 materially exceeds the rate of unwinding of the spring so that whenever the gear 6 is turned the spring 24 will be wound. The secondary spring motor is effective to 5 elevate the link 18 at stated intervals in order that the brake 17 may be released at such intervals whereby the gear 6 is then permitted to rotate to wind the spring 24 as will be fully understood from a description 10 that is to follow.

The brake 17 is normally applied due to the depression of the link 18 and this depression of such link is effected by means of a coiled spring 36 having one end anchored to an arm 37 and the other end in engagement with a bell crank lever 38 mounted at its elbow to turn upon shaft 38¹. Link 18 is connected with one arm of the bell crank. The bell crank arms are substantially at right angles to each other, as shown. The spring 36 is disposed around shaft 38¹ and serves to turn the bell crank in a clockwise direction to depress said link 18 to effect the normal application of the 20 brake 17 to the brake element 16. A second arm 39, fixed with respect to the arm 37 to constitute therewith an arm structure, has a nose 40, (projecting at an angle from the upper end of arm 39 into the plane of rotation of disk 41) that bears upon the periphery of a notched disk 41 (fixed with respect to gear 26). The nose 40 serves to position the arm 37 and its extension 44 and the pin 43 carried by said extension and 30 thereby to position the right hand end (Figs. 5 and 6) of the spring 36 to enable such spring to effect downward pressure upon the link 18. The arms 37 and 39 turn together as a unit upon the shaft 38¹ independently of the bell crank 38. These arms lie between the arms of the bell crank, arm 37 being longer than arm 39. The disk 41 has notches 42 formed therein and as this disk turns with the gear 26 these notches are 40 successively presented to the nose 40 upon the upper end of the arm 39. Whenever a notch 42 is presented to the nose 40 the spring 36 moves the arm 39 inwardly to an extent which is limited by the pin 43 carried upon the extension 44 of the arm 37, this pin intervening between the right hand end of the spring 36 and the left hand arm of the bell crank 38 (Figs. 5 and 6). The 50 downward pressure of the spring 36 upon the link 18 is now eliminated or sufficiently reduced to permit the spring 19 to raise the arm 21 and remove the brake 17 from the brake drum 16. The spring 19, in this operation, also raises the link 18 to complete the inward movement of the nose 40 within the notch 42. The spring 19, when thus functioning, holds the bell crank 38 in its extreme counter-clockwise position.

The disk 45 is rotatable with respect to 60 the rigidly connected gear 26 and disk 41,

said disk 45 being connected with these elements 26 and 41 through the intermediation of the spring 24, it being understood that the disk 45 (together with the pinion 22) is in fixed connection with the shaft 23 to 70 which the inner end of the spring 24 is attached, the outer end of this spring being attached to the spring barrel 25 that is carried by the gear 26. The gear 4 is adapted to wind the spring 24, this gear 4 being 75 driven by the shaft 2 of the main spring motor 1 and performing its spring winding function through the intermediation of the pinion 5, gear 6 and pinion 22. The pinion 22, being in fixed connection with the shaft 80 23, is coupled with the inner end of the spring 24. When the pinion 22 is permitted to rotate the shaft 23 is turned to wind the spring 24. When the pinion 22 is held from rotation, and even during the time it is 85 rotating, the spring 24 reacts against the shaft 23 to operate the load of this spring, this operation of the load of the spring 24 therefore continuing while the shaft 23 and pinion 22 are at rest or while these elements are 90 being turned by the gear 6 to rewind the spring 24. The spring 24 operates its load through the gear 26, rotatable with respect to shaft 23, and the train of gears in which the gear 26 is included. The gears 4, 5 and 95 6 are permitted to turn the pinion 22 to wind the spring 24 during the time that the brake 17 is held released and this brake is held released until the notch 45¹, or 45², in the cam disk 45 (turned by shaft 23) receives the cam roller 46 upon the bell crank 38, whereupon the spring 36 is free to swing the bell crank in a direction to pull the link 18 downwardly to apply the brake 17 to the 100 brake drum 16 to stop the motor 1 to stop 105 the winding of the spring 24. As stated, the disk 41 turns with the gear 26 and with respect to the disk 45. During the unwinding period of the spring 24 this spring turns the disk 41 to a position in which the pin 50 110 upon the disk 41 engages the outer end of the latch arm 48. This engagement of a pin 50 with the latch arm 48 is effective to separate the latch 48¹ from the nose 40 (upon the arm 39) when this nose is in alignment with one of the radial notches 42 in the disk 41 whereupon the spring 36 is free to swing the arm 39 and nose 40 toward the shaft 23, the nose 40 moving in the notch 42. When the arm 39 is thus moved toward the 115 shaft 23 the arm 37 that is in fixed relation with the arm 39 also moves toward the shaft 23 whereupon the pin 43 upon the extension 44 of the arm 37 engages the shoulder 38¹ upon the bell crank 38 to move the bell crank in a direction in which the link 18 will be moved upwardly to lift the brake arm 21 to separate the brake element 17 from the brake element 16 whereupon the spring motor 1 120 is again free to rewind the spring 24 through 125 130

the intermediation of the gearing 4, 5, 6 and 22, this rewinding being concluded when the roller 46 again enters a notch 45¹ or 45² as has been explained. The spring 36 is enabled to perform its function because one of the cam rollers 47 upon the disk 45 engages the arm 37 to cause the pin 48 to place the spring 36 under sufficient tension so that when the notch 45¹, or notch 45², receives the roller 46 said spring 36 is adapted to exert sufficient downward pull upon the link 18 to apply the brake 17 with sufficient pressure to the brake drum 16. When a roller 47 upon disk 45 pushes upon the arm 37 it also moves the arm 39 outwardly, these arms being in fixed relation and when the arm 39 is pushed sufficiently outward its nose 40 is caught by the latch 48¹ that is pressed downwardly by a spring 49 (Fig. 1). This latch operates to hold the arm 39 away from the disk 41 after the operating roller 47 has passed out of engagement with the arm 37 so that the nose 40 cannot drop back into the notch 42 that receives it.

25 The primary or winding motor may have a stiff and long spring adapted, after having been wound up, to wind the spring 24 of the secondary motor many times. The spring 24 may be wound at sufficiently short intervals to enable this spring to exert substantially uniform or constant torque upon the load to be operated thereby. This load may be attached to the secondary motor in any suitable way and while I have illustrated one form of escapement for regulating the speed of operation of this load I do not wish to be limited to the employment of such a device.

By the arrangement illustrated the secondary motor does not have to operate against the force of the brake releasing spring 19 or against the force of the brake applying spring 26, and the force of these springs is uniform irrespective of the tension of the spring of the primary motor. By this arrangement the torque exerted by the secondary motor is practically not interfered with and is uniformly applied to its load.

50 While I have herein shown and particularly described the preferred embodiment of my invention I do not wish to be limited to the precise details of construction shown as changes may readily be made without departing from the spirit of my invention, but having thus described my invention I claim as new and desire to secure by Letters Patent the following:

1. The combination with a primary motor; of a brake for normally checking the operation of the primary motor; a secondary motor which includes a load operating spring with which the first motor is in winding relation; and mechanism for effecting the release of the brake and which is inclusive

of a lever connected with the brake, an arm structure, a spring connecting the arm structure with the lever, and a notched disk driven by the secondary motor and in the notch of which a portion of said arm structure may be received to reduce the tension of said spring upon the brake. 70

2. The combination with a primary motor; of a brake for normally checking the operation of the primary motor; a secondary motor which includes a load operating spring with which the first motor is in winding relation; mechanism for effecting the release of the brake and which is inclusive of a lever connected with the brake, an arm structure, a spring connecting the arm structure with the lever, and a notched disk driven by the secondary motor and in the notch of which a portion of said arm structure may be received to reduce the tension of said spring upon the brake; and a spring operating upon the brake to release it when said portion of the arm structure is received in said notch. 75

3. The combination with a primary motor; of a brake for normally checking the operation of the primary motor; a secondary motor which includes a load operating spring with which the first motor is in winding relation; mechanism for effecting the release of the brake and which is inclusive of a lever connected with the brake, an arm structure, a spring connecting the arm structure with the lever, and a notched disk driven by the secondary motor and in the notch of which a portion of said arm structure may be received to reduce the tension of said spring upon the brake; and a cam element operated by the primary motor for again placing said spring under tension to 90 release the brake. 95

4. The combination with a primary motor; of a brake for normally checking the operation of the primary motor; a secondary motor which includes a load operating spring with which the first motor is in winding relation; mechanism for effecting the release of the brake and which is inclusive of a lever connected with the brake, an arm structure, a spring connecting the arm structure with the lever, and a notched disk driven by the secondary motor and in the notch of which a portion of said arm structure may be received to reduce the tension of said spring upon the brake; and a cam element operated by the primary motor for again placing said spring under tension to 100 release the brake. 105

5. The combination with a primary motor; of a brake for normally checking the operation of the primary motor; a secondary motor which includes a load operating 110

spring with which the first motor is in winding relation; mechanism for effecting the release of the brake and which is inclusive of a lever connected with the brake, an arm structure, a spring connecting the arm structure with the lever, and a notched disk driven by the secondary motor and in the notch of which a portion of said arm structure may be received to reduce the tension 5 of said spring upon the brake; a cam element operated by the primary motor for again placing said spring under tension to reapply the brake; a latch for engaging said arm structure when moved by said cam element; and means operated by the secondary motor for releasing the latch when the brake is to be released.

6. The combination with a primary motor; of a brake for normally checking the operation 20 of the primary motor; a secondary motor which includes a load operating spring with which the first motor is in winding relation; mechanism for effecting the release of the brake and which is inclusive of a lever connected with the brake, an arm structure, a spring connecting the arm structure with the lever, and a notched disk driven by the secondary motor and in the notch of which a portion of said arm structure 25 may be received to reduce the tension of said spring upon the brake; a spring operating upon the brake to release it when said portion of the arm structure is received in said notch; and a cam element operated by the primary motor for again placing said first aforesaid spring under tension to reapply the 30 brake; a latch for engaging said arm structure when moved by said cam element; and means operated by the secondary motor for releasing the latch when the brake is to be released.

7. The combination with a primary motor; of a brake for normally checking the operation 45 of the primary motor; a secondary motor which includes a load operating spring with which the first motor is in winding relation; mechanism for effecting the release of the brake, and which is inclusive of a bell crank lever having one arm connected with the brake, an arm structure, a spring connecting the arm structure with the bell crank lever, and a notched disk driven by the secondary motor and in the notch of which a portion of said arm structure 50 may be received to reduce the tension of said spring upon the brake; and a cam disk operated by the primary motor and operating upon the other arm of the bell crank lever and having formation permitting movement of the bell crank lever by said spring to apply the 55 brake.

8. The combination with a primary motor; of a brake for normally checking the operation 60 of the primary motor; a secondary motor which includes a load operating

spring with which the first motor is in winding relation; mechanism for effecting the release of the brake and which is inclusive of a bell crank lever having one arm connected with the brake, an arm structure, a 70 spring connecting the arm structure with the bell crank lever, and a notched disk driven by the secondary motor and in the notch of which a portion of said arm structure may be received to reduce the tension of said spring upon the brake; a spring operating upon the brake to release it when said portion of the arm structure is received in said notch; and a cam disk operated by the primary motor and operating upon the other arm of the bell crank lever and having formation permitting movement of the bell 75 crank lever by said first aforesaid spring to apply the brake.

9. The combination with a primary motor; of a brake for normally checking the operation of the primary motor; a secondary motor which includes a load operating spring with which the first motor is in winding relation; mechanism for effecting the 80 release of the brake and which is inclusive of a bell crank lever having one arm connected with the brake, an arm structure, a spring connecting the arm structure with the bell crank lever, and a notched disk 85 driven by the secondary motor and in the notch of which a portion of said arm structure may be received to reduce the tension of said spring upon the brake; a cam element operated by the primary motor for again placing said first aforesaid spring under tension to reapply the 90 brake; and a cam disk operated by the primary motor and operating upon the other arm of the bell crank lever and having formation permitting movement of the bell 95 crank lever by said spring to apply the brake.

10. The combination with a primary motor; of a brake for normally checking the operation of the primary motor; a secondary motor which includes a load operating 100 spring with which the first motor is in winding relation; mechanism for effecting the release of the brake and which is inclusive of a bell crank lever having one arm connected with the brake, an arm structure, a 105 spring connecting the arm structure with the bell crank lever, and a notched disk driven by the secondary motor and in the notch of which a portion of said arm structure may be received to reduce the tension of said spring upon the brake; a spring operating upon the brake to release it when said portion of the arm structure is received in said notch; and a cam element operated by the primary motor for again placing said first aforesaid spring under tension to reapply the 110 brake; and a cam disk operated by the primary motor and operating upon the other arm of the bell crank lever and having formation permitting movement of the bell 115 crank lever by said spring to apply the brake.

11. The combination with a primary motor; of a brake for normally checking the operation of the primary motor; a secondary motor which includes a load operating 120 spring with which the first motor is in winding relation; mechanism for effecting the release of the brake and which is inclusive of a bell crank lever having one arm connected with the brake, an arm structure, a spring connecting the arm structure with the bell crank lever, and a notched disk driven by the secondary motor and in the notch of which a portion of said arm structure may be received to reduce the tension of said spring upon the brake; a spring operating upon the brake to release it when said portion of the arm structure is received in said notch; and a cam element operated by the primary motor for again placing said first aforesaid spring under tension to reapply the 125 brake; and a cam disk operated by the primary motor and operating upon the other arm of the bell crank lever and having

formation permitting movement of the bell crank lever by the first aforesaid spring to apply the brake.

11. The combination with a primary motor; of a brake for normally checking the operation of the primary motor; a secondary motor which includes a load operating spring with which the first motor is in winding relation; mechanism for effecting the release of the brake and which is inclusive of a bell crank lever having one arm connected with the brake, an arm structure, a spring connecting the arm structure with the bell crank lever, and a notched disk driven by the secondary motor and in the notch of which a portion of said arm structure may be received to reduce the tension of said spring upon the brake; a cam element operated by the primary motor for again placing said spring under tension to reapply the brake; a latch for engaging said arm structure when moved by said cam element; means operated by the secondary motor for releasing the latch when the brake is to be released; and a cam disk operated by the primary motor and operating upon the other arm of the bell crank lever and having formation permitting movement of the bell crank lever by said spring to apply the brake.

12. The combination with a primary motor; of a brake for normally checking the operation of the primary motor; a secondary motor which includes a load operating spring with which the first motor is in winding relation; mechanism for effecting the release of the brake and which is inclusive of a bell crank lever having one arm connected with the brake, an arm structure, a spring connecting the arm structure with the bell crank lever, and a notched disk driven by the secondary motor and in the notch of which a portion of said arm structure may be received to reduce the tension of said spring upon the brake; a spring operating upon the brake to release it when said portion of the arm structure is received in said notch; a cam element operated by the primary motor for again placing said first aforesaid spring under tension to reapply the brake; a latch for engaging said arm structure when moved by said cam element; means operated by the secondary motor for releasing the latch when the brake is to be released; and a cam disk operated by the primary motor and operating upon the other arm of the bell crank lever and having formation permitting movement of the bell crank lever by the first aforesaid spring to apply the brake.

13. The combination with a primary motor; of a brake for normally checking the operation of the primary motor; a secondary motor which includes a load operating

spring with which the first motor is in winding relation; mechanism for effecting the release of the brake and which is inclusive of a bell crank lever having one arm connected with the brake, an arm structure, a spring connecting the arm structure with the bell crank lever, and a notched disk driven by the secondary motor and in the notch of which a portion of said arm structure may be received to reduce the tension of said spring upon the brake; a cam element operated by the primary motor for again placing said spring under tension to reapply the brake; and a cam disk operated by the primary motor and operating upon the other arm of the bell crank lever and having formation permitting movement of the bell crank lever by said spring to apply the brake, said cam element being carried by said cam disk.

14. The combination with a primary motor; of a brake for normally checking the operation of the primary motor; a secondary motor which includes a load operating spring with which the first motor is in winding relation; mechanism for effecting the release of the brake and which is inclusive of a bell crank lever having one arm connected with the brake, an arm structure, a spring connecting the arm structure with the bell crank lever, and a notched disk driven by the primary motor and in the notch of which a portion of said arm structure may be received to reduce the tension of said spring upon the brake; a cam element operated by the primary motor and operating upon the other arm of the bell crank lever and having formation permitting movement of the bell crank lever by said spring to apply the brake, said cam element being carried by said cam disk.

15. The combination with a primary motor; of a brake for normally checking the operation of the primary motor; a secondary motor which includes a load operating spring with which the first motor is in winding relation; mechanism for effecting the release of the brake and which is inclusive of a bell crank lever having one arm connected with the brake, an arm structure, a spring connecting the arm structure with the bell crank lever, and a notched disk driven by the secondary motor and in the notch of which a portion of said arm structure may be received to reduce the tension of said spring upon the brake; a cam element operated by the primary motor for again placing said spring under tension to

- 6
- reapply the brake; a latch for engaging said arm structure when moved by said cam element; means operated by the secondary motor for releasing the latch when the brake 5 is to be released; and a cam disk operated by the primary motor and operating upon the other arm of the bell crank lever and having formation permitting movement of the bell crank lever by said spring to apply the brake, said cam element being carried by said cam disk.
16. The combination with a primary motor; of a brake for normally checking the operation of the primary motor; a secondary motor which includes a load operating spring with which the first motor is in winding relation; mechanism for effecting the release of the brake and which is inclusive of a bell crank lever having one arm connected with the brake, an arm structure, a spring connecting the arm structure with the bell crank lever, and a notched disk driven by the secondary motor and in the notch of which a portion of said arm structure may be received to reduce the tension of said spring upon the brake; a spring operating upon the brake to release it when said portion of the arm structure is received in said notch; a cam element operated by the primary motor for again placing said first 30 aforesaid spring under tension to reapply the brake; a latch for engaging said arm structure when moved by said cam element; means operated by the secondary motor for releasing the latch when the brake is to be 35 released; and a cam disk operated by the primary motor and operating upon the other arm of the bell crank lever and having formation permitting movement of the bell crank lever by the first aforesaid spring to 40 apply the brake, said cam element being carried by said cam disk.
17. The combination with a primary motor; of a brake for normally checking the operation of the primary motor; a secondary 45 motor which includes a load operating spring with which the first motor is in winding relation; a spring for releasing the brake; mechanism governed by the secondary motor for preventing and permitting 50 the brake releasing operation of said spring; a link connected with said brake; and means governed by the primary motor for pulling upon said link to reapply the brake.
- In witness whereof, I hereunto subscribe 55 my name this eighth day of December A. D. 1916.

KARL R. AKERLUND.
